UNITED STATES PATENT OFFICE

154,984

DESIGN FOR A HANDLE FOR A SADIRON OR SIMILAR ARTICLE

Elmer C. Binggely, Canton, and Dale C. Gerber,
North Canton, Ohio, assignors to The Hoover
Company, North Canton, Ohio, a corporation
of Ohio

Application April 16, 1947, Serial No. 138,440

Term of patent 14 years

(Cl. D49—6)

To all whom it may concern:

Be it known that Elmer C. Binggely and Dale C. Gerber, citizens of the United States, residing, respectively, at Canton, in the county of Stark and State of Ohio, and North Canton, in the county of Stark and State of Ohio, have invented a new, original, and ornamental Design for a Handle for a Sadiron or Similar Article of which the following is a specification, reference being had to the accompanying drawing, forming a part thereof.

In the drawing:

Figure 1 is a top plan view of a handle for a

sadiron or similar article, showing our new design;

Figure 2 is a side elevational view;
Figure 3 is a rear elevational view; and
Figure 4 is a perspective view.

We claim:

The ornamental design for a handle for a sadiron or similar article, as shown.

ELMER C. BINGGELY.
DALE C. GERBER.
